UNITED STATES PATENT OFFICE.

JOSEPH W. BLACK AND GEORGE W. STOUT, OF HANOVER, PENNSYLVANIA.

BUTTER-PRINTING MACHINE.

SPECIFICATION forming part of Letters Patent No. 394,753, dated December 18, 1888.

Application filed June 2, 1888. Serial No. 275,873. (No model.)

To all whom it may concern:

Be it known that we, JOSEPH W. BLACK and GEORGE W. STOUT, of Hanover, in the county of York and State of Pennsylvania, have invented certain new and useful Improvements in Butter-Printing Machines, of which the following is a specification, reference being had to the accompanying drawings, and to the letters of reference marked thereon.

The object of our invention is to provide a machine which will mold butter into prints of a predetermined weight without the need of actually weighing the same; and the invention consists in the several details of construction and arrangement, as hereinafter fully set forth.

In the drawings, Figures 1 and 2 are elevations representing opposite sides of the machine, the lever and printing-block being in different positions. Fig. 3 is an end view of the machine, showing the table in position; and Fig. 4 is a detached detail.

Similar letters of reference indicate similar parts in the respective figures.

A, A', and A² are uprights let into grooves in the base B, and supporting on their upper ends the top C, which is grooved to fit over them, the top and base being tied together by means of the rods b, and the uprights firmly secured to the top and base by pins or screws.

The top C is cut out, as shown in Fig. 4, to form an opening, c, into which the box D is fitted. This box is open at top and bottom, the side pieces extending upward beyond the end pieces and being provided with grooves d on their inner faces.

K is a shelf supported by the bracket k, attached to one end of the box D. This shelf is for the purpose of supporting the sliding cover L, which is adapted to fit in the grooves d and form a top for the box D when necessary. The side d' is cut away at its lower end at d² to give access to the interior of the box, 45 for a purpose to be hereinafter described.

E is the print-block, which is detachably connected to the rack-bar F and fits loosely within the box D. The bar F lies in a groove, a', in the upright A', and is adapted to slide up and down therein, and so give a reciprocal movement to the printing-block E. The up-

rights A' A² are cut out to allow the printing-block to be lowered sufficiently to bring its upper face on a level with the upper face of the top C. The upright A is provided with a slot, a, in which the segmental gear G is mounted on the pin g. This gear G engages with the rack-bar F, and has a lever, H, bolted to it. The top C is also provided with a slot, c', which registers with the slot a and allows 60 the lever to assume a vertical position.

H' is a semicircular support or brace, firmly secured at its lower end to the base B and the upright A, and at its upper end to the top C and box D. This support is provided with a slot, h, in which the stop I is adjustable by means of the screw i and thumb-nut i'. On one side of the lever H is a trigger, J, one end of which is adapted to engage with the stop I, the trigger being held normally in contact 70 with the semicircular support H by means of the spring j. The support H' also serves as a gage, it being provided with marks h' to which the stop I is moved, according as it is desired to make prints weighing half a pound, 75 a pound, or any other predetermined weight, the stop I limiting the throw of the lever, and consequently the vertical movement of the printing-block E.

M is a table detachably connected to the machine by means of the hook m and eye m'. The upper part of the side d' of the box D is provided with a small aperture, d³, for the purpose of allowing any surplus butter to be forced out of the box when molding and printing.

The operation is simple and will be easily understood.

The butter to be molded is placed upon the table M, so as to be readily fed into the box D through the aperture d³. The lever H is brought to a vertical position, as shown in Fig. 1, thereby bringing the upper face of the printing-block level with the upper faces of the top C and table M. The slide L is moved 95 into the grooves d and the stop I adjusted to the requisite mark on the support H'. The butter being fed into the aperture d³, the lever H is depressed and the butter pushed up into the closed portion of the box by means of the printing-block E, where it will be molded into the proper form. The pressure is continued

until the trigger J comes in contact with the stop I, when a print of the intended weight will be in the box D, any surplus having been forced through the aperture d^3 . The slide L 5 is now pushed onto the shelf K, and by pulling the trigger J back against the pressure of the spring j it will pass over the stop I, and by depressing the lever the print of butter will be lifted entirely out of the box, (see Fig. 10 2), when it can easily be removed from the printing-block.

By depressing the lever II to the limit of its movement the printing-block E and rack-bar F can be removed from the machine, and 15 the table being also detachable the whole can be easily washed and cleaned.

Having described our invention, we claim—

1. The combination, with the main frame, of a vertical rack-bar sliding therein and carrying at its upper end a printing-block, a box 20 supported on said frame in which the printing-block reciprocates, a segmental gear mounted in said frame, a lever attached to said segmental gear, a circular support attached to said frame and provided with an 25

adjustable stop, and a trigger on said lever adapted to engage with the said stop, substantially as specified.

2. In a butter-printing machine, the combination, with the main frame, of a box 30 secured thereto, a sliding cover, and a shelf supported by said box and adapted to support the sliding cover when removed from the box, substantially as specified.

3. In a butter-printing machine, the combination, with the main frame, of a box 35 secured thereto, said box being provided with an aperture at the lower end of one of its sides, and a small aperture near the upper end of said side, a table detachably connected 40 to the frame and box, and a printing-block adapted to reciprocate within said box, substantially as specified.

In testimony whereof we have hereunto set our hands and seals.

JOSEPH W. BLACK. [L. S.]
GEORGE W. STOUT. [L. S.]
